Patented Nov. 20, 1973

229,282

CHISEL HANDLE OR THE LIKE

Laird F. Covey, Easton, Conn., assignor to The Stanley Works, New Britain, Conn.

Filed Jan. 10, 1972, Ser. No. 216,914

Term of patent 14 years

Int. Cl. D8—05

U.S. Cl. D8—47

FIG.1

FIG.2

FIG.3

→ 8

FIG.4

FIG.5

FIG.6

FIG.7

FIG.8

FIG. 1 is a perspective view of a chisel handle or the like showing my new design and with the blade in phantom line for illustrative purposes only;

FIG. 2 is a plan view thereof;

FIG. 3 is a side elevational view thereof;

FIG. 4 is a bottom view thereof;

FIG. 5 is an elevational view of the side opposite that illustrated in FIG. 3;

FIG. 6 is an elevational view of the outer end thereof;

FIG. 7 is an elevational view of the blade end thereof; and

FIG. 8 is a cross sectional view thereof along the line 8-8 of FIG. 3.

I claim:

The original design for a chisel handle or the like, as shown and described.
